Inventor:
August W. Melander,

by: *D. Bradburn*
Attorney.

UNITED STATES PATENT OFFICE.

AUGUST W. MELANDER, OF DULUTH, MINNESOTA, ASSIGNOR TO THE EVERSLIDE TIE COMPANY, OF CHICAGO, ILLINOIS, A CORPORATION OF ILLINOIS.

NECKTIE.

1,282,449.

Specification of Letters Patent. Patented Oct. 22, 1918.

Application filed August 2, 1917. Serial No. 184,061.

To all whom it may concern:

Be it known that I, AUGUST W. MELANDER, a subject of the King of Sweden, residing at Duluth, in the county of St. Louis and 6 State of Minnesota, have invented a new and useful Improvement in Neckties, of which the following is a specification.

This invention relates to improvements in neckties, the primary object being to provide a construction of necktie, principally for men's use, which will slip easily in the space between the collar band and flap of a collar to enable easy adjustment and tying of the necktie by the wearer without tearing, or straining it.

More particularly this invention relates to neckties having bands, said bands being usually held in the ordinary turn down collars which are commonly worn.

20 In the accompanying drawing forming part of this specification, Figure 1 is a plan of a four-in-hand necktie constructed in accordance with my invention; Fig. 2 is a cross section taken on the line X—X of Fig. 1; Fig. 3 is a longitudinal section of a detail taken on the line Y—Y of Fig. 1; Fig. 4 is a typical view showing my invention in use, a portion of the collar which is illustrated being broken away to expose a 30 portion of the band of the necktie, and to more clearly illustrate my invention; Fig. 5 is a plan of a detail of an alternative construction; Fig. 6 is a longitudinal section taken on the line Z—Z of Fig. 5; Figs. 7 and 35 8 are cross sections of alternative constructions, and Fig. 9 is a plan view of a detail of another alternative construction of my invention, a portion thereof being broken away to expose a portion thereof.

40 My invention is adapted for use with various kinds of neckties, such as four in hands as illustrated in the accompanying drawing or any other type employing a band portion, which may be inserted and held in turn down collars. As illustrated in the drawing let A represent the band portion of a four-in-hand necktie, and B and C the usual end portions, which as illustrated are of unequal width, but it will be understood that the design of the ends may be varied, and that they may be of equal width when desired, and made out of any suitable material. The band portion of the necktie is of any suitable width and is provided throughout a portion of its length

with an insert D, which is adapted to be held in the turn down collar 2, between its collar band 3 and outer flap 4. This insert is of any suitable width and is preferably made out of a flexible strip of smooth anti-friction material, so that the necktie will slide freely longitudinally in the collar when inserted, and after the collar has been fastened to the shirt of the wearer. This anti-friction strip is preferably although not necessarily composed of a thin strip of cloth fabric 5 forming a base which is covered on both of its sides throughout its entire length by a thin layer of celluloid 6 or any other suitable antifriction material. This structure (see Fig. 2) is formed by first coating with or immersing the celluloid material in a bath of acetone or any other suitable chemical, which will soften the celluloid and cause it to adhere to the fabric when the two 75 are tightly compressed. The strip of celluloid after being treated in the manner stated is folded over the layer of fabric with its outer edges meeting near the longitudinal median line on one side of the strip of 80 fabric. The structure thus formed is then tightly compressed and allowed to dry whereupon a unitary structure is produced having a tough flexible base and a hard, smooth and glossy surface, said structure being flexible, strong, durable and presenting a hard antifriction surface, which will easily slide in the collar between its collar band and outer flap. The antifriction material also reinforces the strength of the band so 85 that the fabric may be comparatively thin and weak and yet slide readily without tearing or straining and the entire tie retain its shape. This structure also produces a substantial means whereby the ends B and 90 C of the necktie can be attached to the ends of the strip of the antifriction band by stitching 7, without tearing or becoming detached under long severe use. The fabric base and celluloid surfacing, constituting 95 the band, having their adjacent surfaces adhesively united throughout their entire area constitute a single element which is more durable, stronger and less likely to crack than if the surfacing were stitched to the 100 fabric and not adhesively secured throughout the entire area, and constituting two distinct elements. The unitary structure of the band is also more sanitary and cleanly than 105 materials like two fabrics were joined or 110

a single fabric used. It also has the flexibility of the fabric but prevents stretching which is a marked advantage.

In using my invention, the tie is easily 5 adjusted with the band portion between the collar band and collar flap in the usual manner and the ends of the tie tied. During this operation the tie can be moved freely without binding, tearing and losing its 10 shape when pulled.

The invention is simple, effective in operation and inexpensive, and fills a long felt want. The construction of the antifriction band D may be variously modified within 15 the spirit of my invention, and I have illustrated several modifications, but it will be understood that they are only illustrative, and that other modifications are also contemplated within the spirit of the invention.

20 In Fig. 7, the antifriction strips 8 and 9, which are made of celluloid or any other suitable material are separate and distinct and overlap the side edges of the fabric 10. They are attached to the fabric under

25 pressure, after first being treated, so as to render them adhesive, the side edges being secured directly together, so as to seal the fabric between them. In Fig. 8, the antifriction strip 11 completely surrounds the strip 30 of fabric 12 and the two side edges are brought together and sealed with the fabric between the sides of the antifriction material. In the construction illustrated in Figs. 5 and 6, the antifriction band 13 has the ends of 35 the antifriction strip formed with flaps 14, which are folded around and sealed to suitable tabs 15 composed of pieces of fabric which project from the ends of the antifriction band and to which the ends such as 16 40 of the necktie are secured by stitching such as 17.

In the construction shown in Fig. 9, the ends of the insert E are shaped and constructed so that the stitching 20 will not 45 crack the material of which the insert is

made. As shown enlargements or lugs 21 are formed on the ends of the insert around which the stitching is passed through the plies 22, said insert being positioned between said plies. An opening or slot 23 across 50 each end of the insert is provided through which the stitching is passed as another means of securing the insert to the tie without cracking. The insert can also be secured to the tie by looping the stitching means 55 at 24 around the space between the lugs 21 and through the plies of the tie. These forms of attaching the ends of the tie to the antifriction band are strong and durable. In all of the structures described, it will be noted that no metallic fastening means is employed for securing the ends of the antifriction insert or band to the ends of the necktie, the construction described providing simple, more effective and less expensive 60 means for securing the insert to the tie without danger of the parts tearing or breaking loose. The antifriction surface also is more sanitary than cloth.

In accordance with the patent statutes, I 70 have described the principles of operation of my invention, together with the apparatus which I now consider to represent the best embodiment thereof, but I desire to have it understood that the construction 75 shown is only illustrative, and that the invention can be carried out by other means and applied to uses other than those above set forth within the scope of the following claim. 80

Having described my invention what I claim as new and desire to protect by Letters Patent is:—

A necktie having tie ends, and a band secured to said ends, said band having a 85 fabric base surfaced with celluloid.

In testimony whereof I have signed my name to this specification.

AUGUST W. MELANDER.
